UNITED STATES PATENT OFFICE

2,016,351

GRINDING APPARATUS

Fay A. Thompson, Colfax, Iowa

Application November 3, 1934, Serial No. 751,314

1 Claim. (Cl. 51—166)

The principal object of my invention is to provide a grinding device that permits the lowering and raising of the grinding wheel holding portion.

5 A further object of this invention is to provide a grinding apparatus that may be easily mounted on an automobile, truck, or like vehicle for portable purposes and when so mounted may use the motive power of the vehicle to rotate its grinding wheel.

10 A still further object of my invention is to provide a grinding device capable of attachment on a vehicle that may be easily and quickly placed in an operative position and as easily and quickly placed in an inoperative condition for transportation.

15 A still further object of my invention is to provide a grinding apparatus that requires little room when not in use.

20 A still further object of my invention is to provide a grinding apparatus that has few parts, is economical in manufacture, and is durable in use.

25 These and other objects will be apparent to those skilled in the art.

30 My invention consists in the construction, arrangement and combination of the various parts of the device, whereby the objects contemplated are attained as hereinafter more fully set forth, pointed out in my claim and illustrated in the accompanying drawing, in which:

Fig. 1 is a top plan sectional view of my complete device ready for use.

35 Fig. 2 is an end sectional view of the method of rotatably securing one end of the grinder housing to a base member.

40 Fig. 3 is an end sectional view of my device with the grinding wheel holding arm in a horizontal position and with dotted lines showing its position when in a vertical position.

45 Grinding apparatuses now being used for the sharpening of plows, discs, and like are of the rigid frame type, making it necessary to lift and hold the item to be sharpened against the grinding element. If the item is heavy, such as units of discs are, this is very difficult of accomplishment. I have overcome such objections by providing a sharpening device that may be moved to and adjusted on the item to be ground.

50 Referring to the drawing, I have used the numeral 10 to designate the elongated housing of the device. The numeral 11 designates a pipe extending at right angles to the main housing 10 and having its inner end secured to and communicating with the inside of the housing.

These two portions 10 and 11 provide a casing of T-construction, as shown in Fig. 1. In this connection, I have found it possible to use the ordinary differential and drive shaft housing of an automobile for the housing, as they provide 5 the desired T-construction.

The numeral 12 designates bearing members in the housing 10. The numeral 13 designates a shaft rotatably mounted in the bearing members 12. This shaft 13 extends beyond one end of the 10 housing 10 and has secured thereon a pulley wheel 14. The numeral 15 designates a bevel gear in the housing 10 and on the shaft 13. The numeral 16 designates bearing members in the member 11. The numeral 17 designates a shaft 15 rotatably mounted in the bearing members 16. This shaft extends completely through the pipe 11 and has on its inner end a bevel gear 18 in engagement with the bevel gear 15. The numeral 19 designates a grinding wheel on the outer 20 end of the shaft 17 and positioned beyond the free end of the pipe 11, as shown in Fig. 1.

In order that the member 11 may be manually moved around a fixed axis, I have provided two bearing members 20 which loosely surround each 25 of the end portions of the housing 10. These bearing members are secured to any suitable base 21 such as a permanent frame in a shop, or the rear springs or like of an automobile. In the drawing, I secure the bearing member 20 to 30 the base 21 by U-bolts 22.

Any motive power may be used to turn the wheel 14 which will, through the shafts and gears, rotate the grinding wheel 19. If the device is secured to an automobile, it may be so 35 adjusted that the pulley wheel 14 engages the rear wheel of the vehicle, or it may be operatively attached by a belt or like. It is then only necessary to jack up the wheel, start the engine, and put the vehicle transmission in gear. By the 40 grinding wheel holding portion being movable, the grinding wheel may be moved to contact the item to be sharpened. When the device is not in use the member 11 may be swung to a vertical out-of-the-way position. 45

Some changes may be made in the construction and arrangement of my improved grinding apparatus without departing from the real spirit and purpose of my invention, and it is my intention to cover by my claim any modified forms 50 of structure or use of mechanical equivalents which may be reasonably included within their scope.

I claim:

In a device of the class described, an elongated 55

housing, a bearing member embracing each end of said housing for rotatably supporting the same, a U-bolt embracing each of said bearing members for securing them to a supporting member, 5 spaced apart bearing members in said housing, a shaft rotatably mounted in said last-mentioned bearing members and having one end extending through and from one end of said housing, a gear wheel on said shaft and inside said housing, 10 a pipe extending at right angles from the cen-

tral portion of said housing and communicating with the inside of the same, bearing members inside said pipe, a shaft rotatably mounted in said last-mentioned bearing members and extending beyond said pipe, a grinding wheel on 5 the outer end of said last-mentioned shaft, and a gear wheel on said last-mentioned shaft, inside said housing, and in engagement with said first-mentioned gear wheel.

FAY A. THOMPSON. 10
